DESIGN FOR A BOTTLE

Frank Earl Higgins, New York, N. Y., assignor to California Perfume Company, Inc., New York,
N. Y., a corporation of New York

Application July 16, 1940, Serial No. 93,678

Term of patent 3½ years

To all whom it may concern:

Be it known that I, Frank Earl Higgins, a citizen of the United States, residing at New York, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a side elevational view;

Fig. 3 is a top plan view; and

Fig. 4 is a bottom view.

I claim:

The ornamental design for a bottle, as shown.

FRANK EARL HIGGINS.
